HACKSAW BLADE MOUNTING

Charles Hubbeck, New York, N. Y.

Application July 14, 1938, Serial No. 219,129

6 Claims. (Cl. 145—34)

This invention relates to what are commonly referred to as hacksaws and particularly to devices of this kind employing means for detachably supporting blades of different kinds and lengths in connection therewith; and the object of the invention is to provide an improved device or pair of devices adapted for mounting in hacksaws of the type and kind under consideration as now constructed so as to provide a simplified means for adjusting the blade into different positions with respect to the supporting frame or mounting to adapt the tool to different uses and more particularly to the provision of a device of the kind described which might be regarded as a replacement part for other devices of this kind which do not employ the simplified features herein set forth; a further object of the invention being to provide a device of the character described wherein adjustments of the blade may be made without removing the blade supporting devices proper from the supporting frame and whereby such adjustments may be quickly and easily accomplished; and with these and other objects in view, the invention consists in a device of the class and for the purpose specified which is simple in construction, efficient in use, and which is constructed as more fully hereinafter described and claimed.

The invention is fully disclosed in the following specification, of which the accompanying drawing forms a part, in which the separate parts of my improvement are designated by suitable reference characters in each of the views, and in which:

Fig. 1 is a side and sectional view showing one form of my improved blade mounting in connection with one standard type of frame.

Fig. 1a is a side view illustrating the form of my invention shown in Fig. 1 in connection with another standard type of hacksaw frame.

Fig. 2 is an enlarged sectional view on the line 2—2 of Fig. 1.

Fig. 3 is a section on the line 3—3 of Fig. 1, omitting part of the construction.

Fig. 4 is a view similar to Fig. 1, showing a modified form of device and omitting part of the construction.

Fig. 5 is a sectional detail view of another form of construction which I employ; and,

Fig. 6 is a side and sectional view of another form of construction.

In Fig. 1 of the drawing, I have shown for the purpose of illustrating one method of carrying my invention into effect, a hacksaw frame 10

consisting of two angular end portions 11 and 12; these end portions having conventional means 13 for detachably coupling the crosshead portions thereof in adjusting the frame to accommodate blades 14 of different lengths. The L-shaped parts 11 and 12 of the frame usually terminate at their ends in angular bearing portions or sockets 15, 16, respectively; and while there are many types and kinds of hacksaw frames, there are two conventional types which are extensively used. One type includes a handle portion 17, such as shown in Fig. 1 of the drawing, which extends outwardly from one end of the frame 10. There are other commonly used so-called pistol grip frames. The grip end portion of one of these frames is shown in Fig. 1a of the drawing. The frame proper 10a is substantially the same as the frame 10 of Fig. 1, but is provided between one angular end portion 11a and the crosshead 13a thereof with a grip portion 18 secured thereto by suitable means, as by rivets 19.

At this time it is well to state that it is one of the features of my invention to provide a blade coupling and adjusting part or device which is universally adaptable to the standard types of frames which are in common use so that this device may be sold as a replacement part or parts to be substituted for the conventional blade supporting means commonly employed. The common blade supporting means which are in use, however, require intricate adjustments or necessitate the entire removal of the blade supporting part in order to change the angularity of the blade in the frame; whereas my improved device will accomplish the desired result without removing the blade supporting device from the frame, and in fact, without removing any of the parts of the complete assemblage.

In Figs. 1, 2 and 3 of the drawing, the device consists of a main device 20 and an auxiliary part 21 of such device. The device 20 comprises an elongated tube or sleeve 22, the end portion 23 of which is square in cross-sectional form to seat in the square bearing 15 as will appear on a consideration of Fig. 3. It will be understood that in this figure part of the structure of the handle 17 has been removed for the purpose of clearly illustrating the bearing 15 as described. The squared end 23 terminates on its outer end in an enlarged head 24 which limits outward movement of the device 20 with respect to the bearing 15. The other end portion of the tube 22 is threaded as seen at 25 so as to engage the

usual threaded ferrule 17a constituting part of the handle 17 as in the usual construction. In other words, the thread 25 will be standard to meet the standard construction of such handles when the device is intended for sale as a replacement or substitute part.

Slidably mounted in the tube 22 is a pin or rod 26 having an enlarged portion 27 adjacent the inner end thereof fitting in an enlarged portion in the bore of the tube so as to operate upon a spring 28, the spring normally urging the pin 26 inwardly. The inner end of the pin is provided with a coupling head 29 which is in the form of a cylinder which is cut away to the center thereof as seen at 30 forming a blade receiving socket. This socket is bounded on one wall by an inwardly protruding hook 31 which forms a means for retaining the blade 14 against accidental displacement when the parts of the device are loosened for the adjustment of the blade. The head 29 is provided with a pin 32 which extends into the socket 30 so as to engage an aperture 14a in the end of the blade 14. With this type of construction, it will be understood that the blade 14 will require slight flexure for attaching and detaching the same with the coupling head 29. In the construction shown in Figs 1 to 3 inclusive, the outer end of the pin is threaded as seen at 33. Mounted on this threaded end is a ratchet sleeve 34 which is also preferably keyed to the pin or rod 26 by a transverse pin 35. The ratchet 34 is also externally threaded to correspond with the threads of the tube 22 so that the entire device is free to enter the ferrule 17a.

The inner surface of the ratchet 34 is provided with circumferentially spaced teeth adapted to register with corresponding teeth formed in the outer end of the tube 22 as indicated at 36 so that the pin 26 is free to be rotated in one direction but will be retained against rotation in the opposite direction. The other part 21 of the complete device is in the form of a round pin 37 which fits freely in the bearing or socket 16 and is provided at its outer end with a head 38 seating upon the bearing to limit inward movement of the pin. The pin 37 has a coupling portion 39 which corresponds to the coupling head 29 in every respect so as to mount the other end of the blade 14. The head 38 may also be provided on the inner surface thereof with circumferentially spaced beveled teeth 38a which will aid in retaining the pin 37 in different positions of adjustment while the blade is under tension and which will permit free rotation of the pin in the adjustment of the blade when the tension on the blade is relieved.

In the use of the device described, it will be understood that the handle 17 operates to support the blade 14 under tension within the frame; the ferrule 17a drawing the device 20 outwardly in accomplishing this result in the operation of tightening the handle. However, when it is desirable to adjust the blade into different positions or to remove a blade and substitute a new or other type and kind of blade, the handle 17 is loosened by screwing the same outwardly. This operation will permit inward movement of the device 20 thus loosening the blade 14; and when so loosened adjustment may be provided by simply rotating the coupling 29 to bring the blade in the desired position. In this rotary movement, the ratchet sleeve 34 will simply snap over the teeth on the tube 22 until the blade is in proper position, the spacing of the teeth being such as to provide

any desired angularity of the blade, four different positions being illustrated in the accompanying drawing. However, any number of positions may be provided. After the desired adjustment of the blade has been made or after a new blade has been substituted, the handle 17 may be again rotated so as to tighten the blade in the usual manner. It will be understood that no rotary movement is transmitted to the coupling 29 in this operation, and no rotary movement is transmitted to the tube 22 but this tube will move outwardly in the bearing 15. In the above adjustment of the blade, it will be understood that the associated part 21 will be correspondingly rotated, the handle being sufficiently loosened to compensate for the movement of the parts.

In Fig. 1a a pistol grip frame has been shown as provided in the socket 15a thereof with the same adjusting device 20 as is shown in Fig. 1. In Fig. 1a, however, a suitable nut 40a is employed in place of the ferrule 17a of the handle 17 shown in Fig. 1 as the means for tightening the device 20 together with the blade 14 in the frame. The nut 40a is preferably of knurled type, but may be of the wing-nut or other suitable type in accordance with conventional practices. The operation of the device as applied to the pistol grip frame is exactly the same as previously described in connection with Figs. 1 to 3.

The device as disclosed in Figs. 4 to 6 inclusive is adapted for use in connection with a hacksaw of the pistol grip type. With this type of construction, the blade 14 or the coupling 29 may be rotated when the nut 40 is loosened or the ratchet 34 may be rotated by hand engagement to adjust the blade. However, it is preferred that a supplemental nut such as shown at 41 in Fig. 5 of the drawing be employed in such cases; this nut being attachable and detachable with respect to the ratchet 34. An inturned flange 40a is provided on the nut to limit inward movement thereof.

In this connection another adaptation of the device primarily for use in the pistol grip type of frame is shown in Fig. 6 of the drawing, wherein an operating knob 42 is disclosed which consists of an enlarged knurled head 43 and a sleeve portion 44 having ratchet teeth 45 similar to the teeth employed on the sleeve 34. In other words, with this construction, two parts will be formed integrally and the outer end of the pin 26a which is otherwise similar to the pin 26 will be unthreaded. The knob 22 will be either driven onto the pin 26a or secured thereto by a set screw indicated at 46. In the structure shown in Fig. 6, the nut 40 is also illustrated as arranged upon the threaded portion of the tube 22; the latter being identical with the structure shown in the other figures.

In Fig. 4 of the drawing, the device is shown on an enlarged scale with the tube 22 in elevation. The device in this construction differs from that shown in Figs. 1 to 3 inclusive simply in substituting for the externally threaded ratchet 34, a ratchet 34a having a plain or angular end 34b, which would form a finger piece facilitating rotation of the blade. It will be understood, however, that in any case the blade itself or the coupling 29 may be directly rotated. With this type of construction and by virtue of the reduced size of the ratchet 34, the same is free to pass into the handle 17 without engaging the threads of the ferrule 17a. At the same time attachment and detachment of the nut 40 will

be permitted without the need of uncoupling the ratchet 34a from the pin 26.

All of the forms shown will be adaptable for use in conjunction with tools of the standard or conventional constructions with the exception of the structure shown in Fig. 3, which is adapted primarily for the pistol grip type of tool. It will be understood in this connection that the structure of Fig. 5 while being adapted for the pistol grip tool can also be used in the other types of tools by simply removing the nut 41. In this structure, it is also to be noted that a plain pin 26a such as shown in Fig. 6 is also used, and the ratchet 34 is secured to the pin by a transverse key pin 35a similar to the pin 35.

It will be understood that while certain embodiments of my invention are illustrated in the accompanying drawing, other changes in the specific form of the respective parts of the device may be made, especially in adapting the same to special types of hacksaw frames. However, in the respective uses of the device, it is my intention to provide a tool mounting means for any type or kind of frame which will permit of the adjustment or replacement of the tool without detaching the tool engaging means from the frame and also in providing a quick and simple means for performing the desired function.

It will be understood that in the movement of the blade into taut position, the tightening of the ferrule 17 or the nut 40 operates to draw the sleeve 22 outwardly in the bearing or socket 15. In this outward movement, the outer ratchet end of the sleeve engages the ratchet on the pin and thus operates to draw the pin including the coupling head 29 thereof outwardly. When the blade is in its taut or clamped position, the ratchet prevents rotary movement of the pin and the coupling 29. It will be apparent that the setting of the ratchet will maintain the proper alignment of the blade in the frame with the teeth of the blade extending in the proper direction. In this manner, it will also be noted that in loosening the device for adjustment and otherwise, it is only sufficient to provide for the free movement of the ratchet to rotate the pin carrying the coupling 29, and of course sufficient to permit rotation of the pin 37.

Having fully described my invention, what I claim as new and desire to secure by Letters Patent is:

1. An attachment for a conventional hacksaw frame providing for the adjustment and replacement of a blade without removing the attachment from said frame, said attachment comprising an elongated threaded sleeve, predetermined external wall portions of said sleeve being flattened for keying the same in one part of said frame to permit longitudinal movement only of the sleeve therein, threaded means on said sleeve operatively bearing against said frame for controlling the longitudinal movement of said sleeve, a blade coupling element rotatable and longitudinally movable in the sleeve, a coupling member at one end of said element for attaching one end of a blade therewith, ratchet means at the other end of said element engaging corresponding ratchet means on said sleeve, a spring holding the ratchet means on said element and sleeve in resilient engagement, the shape of said ratchet means being such that said spring in conjunction with said ratchet means prevents rotary movement of said element in one direction while permitting rotary movement thereof in the other direction when said threaded means has been

moved to a position out of engagement with said frame.

2. An attachment for hacksaw blade frames providing adjustment and replacement of a blade without removing the attachment from the frame, said attachment comprising an elongated threaded sleeve, means for keying the sleeve in one part of the frame to permit longitudinal movement only of the sleeve therein, movable threaded means on said sleeve having a shoulder thereon adapted to bear against said part of the frame, a blade coupling element supported in said sleeve for longitudinal and rotary movement with respect thereto, a coupling member at one end of said element for attaching one end of a blade therewith, resilient means between said sleeve and coupling element for normally urging said element in the direction of said coupling member, cooperating ratchet means at the other end of said element and on said sleeve, said ratchet means supported in yieldable engagement by said resilient means, and said ratchet means being supported in positive engagement when a blade is supported in taut position by firm engagement of the shoulder on said sleeve with said frame.

3. A blade supporting device for a hacksaw frame of the class described having rotatable blade engaging means at one end thereof, said device including a threaded sleeve adapted to be slidably keyed in the opposed end of the frame, a blade engaging member extending through said sleeve, blade engaging means at one end of said member, enlarged means at the other end of said member adapted to register with corresponding means on the end of said sleeve in predetermined positions of rotation of said member with respect to said sleeve, means disposed between said sleeve and blade engaging member adapted to resiliently urge said sleeve in the direction of the enlarged means on said member, and adjustable means on said sleeve cooperating with said frame for independently urging said sleeve in the direction of the enlarged end of said member in the operation of firmly supporting a blade in said frame.

4. In combination with a hacksaw frame of the character described means for detachably and adjustably mounting blades in said frame without detaching said means therefrom, said means comprising a freely rotatable member in one part of the frame having means for engaging one end of a blade, and a device comprising an externally threaded sleeve slidably and non-rotatably supported in another part of the frame, a blade coupling member having means at one end thereof for engaging the other end of the blade, said blade coupling member being rotatable in said sleeve and relatively movable longitudinally thereof and of said last named part of the frame, an enlarged portion at the other end of said coupling member and cooperating with said sleeve for limiting movement of said sleeve in the direction of said enlarged portion, adjustable means on said sleeve and cooperating with said last named part of the frame for moving said sleeve into firm engagement with the enlarged portion of said coupling member and for collectively moving said sleeve and member in the direction of said enlarged end to tighten the blade in the frame, and means for locking the coupling member against rotation with respect to the sleeve when the blade is supported in taut position.

5. In a hacksaw frame having rotatable means at one end portion thereof for engaging one end

of a blade, an attachment for the other end portion of said frame providing for rotary adjustment and replacement of the blade without removing the attachment from the frame, said attachment comprising an elongated threaded sleeve, means for keying the sleeve in said last named portion of the frame against relative rotation while permitting longitudinal movement of the sleeve therein, a blade coupling element 5 rotatable in said sleeve and relatively movable longitudinally thereof and of said portion of the frame, a coupling member at one end of said element for engaging the other end of the blade, ratchet means at the other end of said element 10 engaging corresponding ratchet means on said sleeve to prevent rotation of the element when the blade is supported in taut position, said ratchet means forming stop shoulders limiting the relative longitudinal movement of said sleeve and element, movable threaded means on said sleeve forming a shoulder thereon abutting the outer end of said last named portion of the frame, and said movable threaded means through

said sleeve and stop shoulders controlling the longitudinal movement of said sleeve and element relative to said part of the frame in the operations of tightening and loosening the blade supported therein.

5

6. A blade supporting device for conventional hacksaw frames of the class described, said device comprising a blade coupling element having a blade coupling member at one end thereof, means at the other end of said element for controlling rotary movement of said element, means 10 slidably arranged in the frame for supporting the element, an adjustable member on said last named means and abutting the frame for controlling relative movement of said means in the frame, said first named means comprising a ratchet adapted to engage corresponding ratchet means on said element supporting means, and said ratchet also forming a stop shoulder adapted to communicate to said coupling element the 15 longitudinal movement imparted to said supporting means by said adjustable member.
